UNITED STATES PATENT OFFICE.

WILLIAM CHARLES WILLIAMS, OF WINNIPEG, MANITOBA, CANADA.

ELECTRIC WATER-HEATER.

1,217,380.

Specification of Letters Patent. Patented Feb. 27, 1917.

Application filed August 16, 1915. Serial No. 45,721.

To all whom it may concern:

Be it known that I, WILLIAM CHARLES WILLIAMS, a citizen of the Dominion of Canada, residing at the city of Winnipeg, in the Province of Manitoba and the Dominion of Canada, have invented certain new and useful Improvements in Electric Water-Heaters, of which the following is a specification.

10. My invention relates to water heaters for domestic use, such as may form part of a single line piping system to heat the water passing therethrough in the running stream at such times as hot water may be required.

15. the heater control being arranged in such manner that the apparatus may be placed in and out of operation from any part of the building in which it may be installed, so that either hot or cold water may be drawn from the same faucet according to whether the heater is in or out of operation.

20. The primary object of the invention is to arrange the apparatus in accordance with the above requirements and so do away with the double piping now in general use in hot and cold water supply systems. A further object of the invention is to so construct the heater proper that all the parts thereof are easily accessible for repair or renewal.

25. The means by which these objects are attained will be found fully set out in the following specification and more particularly pointed out in the appended claims, reference being also had to the accompanying drawings which form a part hereof and in which similar characters of reference refer to similar parts throughout the different views. Referring to these:

Figure 1 is a view in perspective of the heater with the control means shown diagrammatically in connection therewith.

Fig. 2 is a view taken on the line A—A of Fig. 1 and showing one form of piping therein.

45. Fig. 3 is a side elevation of the base of the heater apart from the rest of the apparatus.

Fig. 4 is a view taken on the line A—A in Fig. 1 and similar to Fig. 2 but showing 50 the preferred form of piping therein.

Fig. 5 is a view from above of the piping and parts of the heater pertaining thereto shown in Fig. 4, but removed from connection with all other parts of the device.

Fig. 6 is a plan view of the base showing 55 the heating coils therein.

Fig. 7 is an interior view of the chambers with which the pipes communicate.

Fig. 8 is one of the plates in which the pipes terminate.

Fig. 9 is a separate view of one of the return bend pipes as shown in Fig. 2.

Fig. 10 is a fragment of one of the end plates showing a semi-circular projection which might be placed thereon and around 65 which the bends of the pipes might be made.

The heater proper comprises three principal parts, a base B, water container C and cover D, all of which are quite distinct and separable from each other.

70. The part C consists of a pair of heads or plates 1 and 2 spaced apart and rigidly connected by angle iron corner pieces 3 to form a frame, the plates being apertured as at 4 in Fig. 8, to receive the tubes 5 which extend 75 across the space between the plates. The tubes may be of a length to reach across between the plates and have a bearing therein as shown in Fig. 4, in which case their ends are expanded in the apertures 4 in the usual 80 manner of such connections, to secure a tight joint. The tubes are placed in rows and tier above tier, and there may be as many tubes in a row and as many tiers of tubes as may appear advisable.

85. Castings 6 and 7 (shown separately in Fig. 7) are shaped to afford chambers 8 and 9 separated by a partition 10, the chambers having a flange 11 all around provided with apertures 12 adapted to register with similar apertures 13 in the plates 1 and 2 through which bolts 14 may be passed to secure them together, packing strips 15 being inserted between the meeting parts of the castings and plates to form a water tight 90 joint therebetween.

95. It will be noted that the castings 6 and 7 are exactly alike and that each has an opening 16 in its rear wall communicating with the smaller chamber 9 therein, the openings 100 being interiorly screwthreaded for connection with a pipe.

The casting 6 is secured to the plate 1 with the smaller chamber 9 at the bottom, the casting 7 being secured to the plate 2 in the 100 reverse position. A pipe 17, being screwed into the opening 16 in the casting 6 forms a connection between the heater and a suitable

source of water supply, while a pipe 18 similarly connected with the chamber 9 in the casting 7 runs from the heater to the various faucets in the building. Thus the water entering the chamber 9 in the casting 6 from the pipe 17 passes through the lower tier of pipes into the chamber 8 in the casting 7, thence back through the center tier of pipes into the chamber 8 in the casting 6, then into the chamber 9 in the casting 7 by way of the upper tier of pipes and out through the pipe 18 to the various points of consumption.

It will be understood that while the plumbing forms no part of the present invention, it is preferable that the heater be connected into the supply pipe by means of union couplings at each side, and that a bypass be arranged around the heater, with suitable valves, so that the heater may be disconnected from the pipe line at any time without disturbing the water supply.

The alternative form of piping shown in Fig. 2 provides the pipes 5 of a length suitable to pass back and forth through the apparatus, the number of times required, the return bends 19 in the pipes taking the place of the chambers 8 in the previously described construction. In this form the end plates 1 and 2 may have projections 20 as shown in Figs. 2 and 10, occupying the space between the tier pipe-openings, around which the return bends 19 of the pipes may be made, the pipes being preferably of copper and easily bent, and the projections may further be provided with grooves on their peripheries, indicated as 21, to retain the bends in place. The extreme ends of the pipes in this construction, 40 would be expanded in the plates at their point of communication with the chambers 9 in both the members 6 and 7.

The portion C of the apparatus is supported by the pipes 17 and 18 and a shelf 45 is usually provided at a suitable distance below it on which the base B is positioned. The base B it will be noted, is provided with legs 22 and 23 secured thereto by bolts 24 and 25, those 25 being easily removable so that the legs may be turned up as indicated by the dotted lines in connection with the leg 23 in Fig. 3 and the base thus lowered from its connection with the portion C of the apparatus.

55 The base B is in tray form, this consisting of a bottom 26 surrounded by an upwardly projecting flange 27, around which the cover D fits, the flange being provided with outwardly projecting studs 28 and the cover with slots 29 in which the studs engage when the cover is placed in position. The cover is further slotted at each end from the bottom upwardly for the reception of the pipes 17 and 18, a pivoted cover 30 being provided for the slot 31 pertaining to

the pipe 18, and a similar arrangement being made for the pipe 17 at the opposite end of the cover, so that the slots may be covered to conserve the heat after the pipes are received therein.

70 A sheet 32 of non-conducting material, preferably asbestos board, is placed upon the bottom 26 of the base and secured thereto by bolts 33, and a plurality of resistance coils 34 are secured on the surface of the sheet 32 and connected preferably in series, their terminals being further connected with the wires 35 and 36.

The wires 35 and 36 run to a double pole switch 37 by means of which they may be 80 connected with the mains 38 and 39 which are in circuit with a source of electric current which may be drawn upon to energize the coils 34 thus heating the interior of the apparatus and the water passing through 85 the pipes therein.

To operate the switch 37 an electro-magnet 40 is conveniently placed with reference thereto and the switch blades 41 are provided with an armature 42 positioned to be 90 actuated by the magnet when energized to close the main circuit, and a tension spring 43 is provided to release the blades 41 from the contacts 44 when the magnet 40 is de-energized.

95 The coil 40 is wired in a circuit which includes a battery 45, the wires 46, 47 and 48 of the battery circuit being carried to the various apartments of the building where water is used and one of the switches 49 provided in the circuit adjacent each faucet. Pilot lamps 50 are also provided in the battery circuit, one at each faucet, to indicate when the heater is in operation. It will be noted from the diagram that when any one 105 of the switches 49 is closed all of the pilot lamps will be energized thus indicating in all the apartments that the heater is in operation.

110 From the foregoing description it will be seen that the heater proper provides in compact form means for heating the water in a running stream; that the battery circuit, with the switches therein, provides means whereby the electro-magnetically controlled switch 37 may be operated from any part of the building to heat the water; and that by reason of these provisions a person may draw water of any temperature ranging from cold to very hot, from any faucet 115 in the building, by merely regulating the flow from the faucet to run freely or to pass through the heater slowly to raise its temperature.

120 Having thus fully described my said invention, what I claim is—

1. A heater comprising in combination, a stationary water-tube boiler having outlet connection with a house service by which the flow of water through the boiler is con- 130

trolled, a removable base normally in contact with the under side of the boiler, a casing inclosing the boiler and detachably connected with the base, and electrically operated means in the base to heat the boiler.

2. A heater comprising in combination, a water tube boiler, a base, means normally supporting the base in contact with the boiler, a casing surmounting the base and 10 detachably connected therewith to form with the base a chamber in which the boiler is contained, a plurality of resistance coils in the base, and electro-magnetically operated means by which the coils may be energized to heat the chamber.

3. A heater comprising in combination a water-tube boiler having inlet and outlet pipes connected therewith and by which it is supported; a base normally in contact 20 with the boiler and having legs adapted to be turned up to remove the base from contact with the boiler; a casing surmounting the base and detachably connected there-

with to form with the base a chamber in which the boiler is contained, said casing 25 having slots in the ends thereof to receive the inlet and outlet pipes and members pivoted to the casing to cover the slots when the casing is in position on the base; and electrically operated means in the base to 30 heat the boiler.

4. A heater comprising in combination, a suitably supported water-tube boiler, a removable base normally in contact with the boiler, a casing detachably connected with the base and inclosing the boiler, a plurality of resistance coils arranged in the base, electro-magnetically operated switch means by which the coils may be connected with a source of electrical energy, and electrical means coöperative with the switch means to indicate at various points when the apparatus is in operation.

In testimony whereof I affix my signature.

WILLIAM CHARLES WILLIAMS.
